United States Patent Office.

CHARLES H. WARREN, OF TOLEDO, OHIO.

Design No. 3,531, dated June 1, 1869.

DESIGN FOR A TRADE-MARK.

The Schedule referred to in these Letters Patent and making part of the same.

To all whom it may concern:

Be it known that I, CHARLES H. WARREN, of Toledo, Lucas county, and State of Ohio, have originated and designed a new Design for a Trade-Mark, more especially to be used upon churns, pails, and tubs, and other articles of a like construction, of which the following is a full, clear, and exact description, reference being had to the accompanying specimens, taken by the photographic process, making part of this specification.

In the accompanying specimens, my invention, or design is shown upon a churn, and consists in the employment of the capital Roman letters O C with a de-

sign, or sketch of an eye, interposed between said letters, so that the design would read, were the Roman letter I employed instead of the design of an eye, "Oh, I see."

I also paint the metallic hoops in a red color, and brand them with the words, "Trade-mark, red hoop."

What I claim as my invention, and desire to secure by Letters Patent, is—

The design for a trade-mark herein set forth.

C. H. WARREN.
